UNITED STATES PATENT OFFICE

2,575,206

FACE LIFTING DEVICE

Adolph M. Brown, Chicago, Ill.

Application March 30, 1950, Serial No. 152,842

2-Claims. (Cl. 128—76)

1

This invention relates to a temporary method for eliminating or minimizing facial senescence and to a device for accomplishing the same.

In my copending applications, Serial No. 64,817 and 64,818, filed on December 11, 1948 and Serial No. 119,970, filed on October 6, 1949, description is made to a device and to a method for securing the effect of a face lift without being subject to the expense and to the dangers inherent in such surgical means for eliminating loose skin on the human face. The devices used in the practice of the invention described in these copending applications, rely upon the engagement of spur members in the scalp, and a resilient force constantly urging pairs of such anchor members in the direction toward each other, thereby to retract loose skin from the face. Devices of this type function in a desirable manner to relieve or eliminate facial senescence, but the characteristic of skin penetration by the spurs make them distasteful to many for whom their use is intended.

It is an object of this invention to provide a method and a device for retracting loose skin from the face without requiring skin penetration for proper operation.

Another object is to provide a new and improved method for the elimination of wrinkles and facial senescence, and it is a related object to provide the means for carrying out the same, including means for exposing spaced portions of the scalp within the hair line, means for proper application of an adhesive coating to the exposed portions of the scalp and the anchorage thereto of a conforming anchor member, which, responsive to forces operating to press the anchor member inwardly and upwardly, creates frictional forces which aid in preventing slippage of the anchoring member when in position of use while actuating the adjacent skin parts upwardly to retract loose skin from the face.

These, and other objects and advantages will hereinafter appear and for purposes of illustration but not of limitation, an embodiment of the invention is shown in the accompanying drawings in which,

Figures 1-4 illustrate steps employed in the practice of this invention.

Figure 5 is a perspective view showing the comb member in position of use.

Figure 6 is a perspective view of the applicator which forms part of the apparatus used in the practice of this invention.

Figure 7 is a top plan view of the anchoring member.

Figure 8 is a sectional view taken along the line 8—8 of Figure 7.

Figure 9 is a side elevational view of the anchor member shown in Figure 7.

Figure 10 is a sectional view taken along the line 10—10 of Figure 7 and

Figure 11 is a perspective view of the head strap which joins a pair of anchoring members.

In accordance with this invention, the hair 10 along the hair line adjacent the temples is combed in an upward direction to arrange the hair in tufts in parallel spaced rows with exposed scalp therebetween. An adhesive is applied to the exposed skin portion and then an anchoring member, having bars fixed in side by side parallel relation and spaced to correspond with the spacing of the rows of exposed scalp and having adhesive applied to the under side, is engaged with the skin portion coated with the adhesive. The anchor members mounted in this relation on each side of the head are tensioned in the upward and inward direction by reaction through a connecting head strap which operates as an adjustable spring strap to exert medial pressure. The reactive forces increase the anchoring relation of the anchoring member while causing it to withdraw loose skin away from the face.

The parts which make up the device embodying features of this invention are illustrated in Figures 5-10 inclusive. Figures 1-4 illustrate the method by which the parts may be used in carrying out the invention.

Figure 5 shows a comb member having a handle portion 10 and coarse teeth 11 in widely spaced apart relation along the head portion 12 of the comb. When the hair adjacent the temple is combed upwardly, the hair is arranged in spaced apart tufts 13 and the scalp 14 is exposed therebetween such that an adhesive 15 may be applied thereto.

The adhesive is applied by means of an applicator member 20, shown in Figure 6, which is a rigid unitary structure having an arcuate handle portion 21 with curved portions 22 arranged in the side walls to provide a better finger grid. A plurality of rigid strips or bars 23 formed of plastic, metal, wood, or the like are fixed crosswise to the under side of the handle 21 in spaced apart parallel relation. The width of the strips or bars 23 is calculated to correspond to the width of the scalp portion exposed by the comb and the spaced relation between the bars 23 is adapted to correspond to the width of the hair tufts. For proper operation, the width of

the bars may be less than the exposed scalp portion in order to prevent the possibility of adhesive application to the hair disposed therebetween. The under side of the bars 23 are preferably flat, and they are used in the described process to transmit adhesive from a pad or other supplying means to at least a part of the exposed scalp portion 14 between the hair tufts 13. As shown in Figure 6, the lower edge portion of the handle 21 may be curved as at 24 in the area between the bars 23 to provide more space in which the combed tufts of hair may be located during application of the adhesive.

The anchor member comprises a plurality of strips or bars 30 corresponding in length and width with those of the applicator, previously described. The bars 30 are fixed in crosswise spaced parallel relation along the under side of the rigid crossarm 31 and means are provided on the crossarm for mounting the unit on the end of a resilient head strap 32 in a manner to permit free swivelling movement in any direction, as by a universal joint such as the ball 33 and socket joint 34 shown in the illustrated drawings. Instead of such ball and socket joint, any other pivotal connection well known in the art may be used.

The under side of the bars 30 may be flat, but it is best to provide a serrated surface, such as the toothed arrangement 34 shown in Figure 8 with the sharp offset 35 facing in the direction in which the anchor member will be urged when in position of use. The roughened surface is adapted to establish a firmer gripping relation with the surface of the scalp without piercing it. It is preferred to augment this gripping relation by the use of an adhesive applied to the under side of the bars 30—the adhesive being selected to cooperate with the adhesive applied to the scalp in effecting a bonded relation upon contact, but not to have adhesive characteristics when separate therefrom.

In the practice of this invention, a pair of such anchoring members is used. They are connected by head bands 32 formed of curvilinear spring metal strips 40 and 41, the outer ends of which pivotally mount the described anchor members while the overlapping inner end portions are adjustable by means of loops 42 fixed to the respective ends of the strips 40 and 41 and through which the intermediate portions of the strips are slidable. The described relationship with respect to the looped members and the strap portions extending therethrough, operates to establish frictional engagement when actuated to the adjusted position, such as by the palms of the hands. The assembled head bands 40 and 41 conform to an arc of a true circle, but they are formed to elliptical shape such that when the straps are pressed toward the middle position of the head, the anchoring elements will be urged inwardly and upwardly as they pivot from the center. By so adjusting the straps, after the anchoring elements have been located in position of use, the anchor elements will be pressed inwardly and upwardly thereby to establish a firmer gripping relation by friction and to retract loose skin away from the face.

Other than the spring metal straps 40 and 41 of which the head band is formed, the parts described herein are formed of rigid material such as metal, wood, plastics or the like. As shown in Figure 4, instead of a single head band connecting the pair of cooperating anchor elements, two or even more head bands may be pivoted

from spaced portions of each anchoring member to provide a firmer gripping relation along the head and also to provide for a variable operating relation. That is, one head band may be tensioned more than the other to effect greater retraction in certain portions of the contacted scalp than the other.

When an adhesive system is employed in combination with the described device, it is desirable to have a non-allergic adhesive and it is also preferable to have a pressure sensitive adhesive which exhibits adhesive properties only when contacted with another body corresponding thereto. One such adhesive system includes a latex base emulsion type adhesive which may be used for application to the scalp and a rubber base cement which may include a solvent for application to the under side of the bars 30. To mark the scalp portion coated with adhesive, it is best to use an adhesive that is colored.

In carrying out the invention, the hair at the hair line just above the temple region is combed upwardly as shown in Figure 1 to arrange the hair in spaced apart tufts, illustrated in greater detail in Figure 5. When the desired hair arrangement has been established, the comb is allowed to remain at the upper region of its stroke, in order to retain the tufts of hair in the desired relation. In the meantime the applicator 20 is pressed on a stamp pad wet with an adhesive such that the adhesive may be transferred from the pad to the under side of the bars 23. Because of the conforming pressed relation between the bars 23 and the exposed scalp 14, adhesive may be transferred to the exposed scalp portion by a single application of the applicator as shown in Figure 2.

While the applied adhesive is drying, the comb is still allowed to remain in place, and adhesive is applied to the under side of the bars 30 of each anchor member. When both adhesive layers have dried sufficiently, the anchor member may be fixed to the scalp by pressing the conforming coated surfaces together, as shown in Figure 3.

In the same manner, the other anchor member is adhered to the scalp portion above the temple hairline. In the event that the head parts are disconnected from the anchoring members, they may be snapped into engagement such that the head bands will encircle the cranium. When this relationship has been established, it is only necessary to cause a contraction of the head bands in the usual manner as with the palm of the hand. Depending upon the extent of adjustment of the head strap force, reactions are set up between the anchoring members which exert pressure medially and traction upwardly or superiorly. These forces tend to minimize possible slippage of the anchoring members, because of the greater frictional resistance relative to movement, while the upwardly acting force operates to retract loose skin from the face and give the effect of a face lift, as shown in Figure 4.

At this point, the combs holding the hair apart may be removed and then the hair may be combed down over the parts described in order to effect substantially full concealment. Concealment will be aided by the use of parts which are colored to conform to the coloring of the hair.

It will be manifest that I have provided new and improved apparatus and a method for minimizing facial senescence in a practical and easy manner without being subject to the objectionable features of skin penetration and the like.

From the description, it will be apparent that the described method will not be subject to the objectionable features of a face lift and that variability with respect to the type and amount of skin retraction can be secured by simple adjustment or by modification in the method in which this invention is practiced. For example, it will be possible to secure modified effects by fixing the anchoring members to different parts of the scalp and that modified effects may be secured by urging only certain portions of the anchoring members in the upward direction.

It will be understood that numerous changes may be made in the details of construction, arrangement, and operation, without departing from the spirit of the invention, especially as defined in the following claims.

What is claimed is:

1. In a device for minimizing facial senescence an anchoring member comprising a rigid cross arm, a plurality of rigid bars arranged in spaced parallel relation to the underside of the cross arm and transversely thereof, the underside of the bars having means for minimizing slippage on

skin surfaces when in contact therewith, and means on the cross arms for pivotally connecting the anchoring member to a head band.

2. In a device for minimizing facial senescence, an anchoring member comprising a cross arm, a handle portion fixed to the cross arm, a plurality of rigid bars fixed in spaced parallel relation to the underside of the cross arm, the underside of the bars being grooved transversely to provide sharp offsets facing the same direction, and means in the handle for pivotally connecting the anchoring member to a spring metal strap encircling the head.
